UNITED STATES PATENT OFFICE.

NATHAN B. ABBOTT AND JOHN P. CRANFORD, OF BROOKLYN, NEW YORK.

IMPROVEMENT IN CROSSINGS FOR COMPOSITION PAVEMENTS.

Specification forming part of Letters Patent No. 175,318, dated March 28, 1876; application filed January 21, 1876.

To all whom it may concern:

Be it known that we, NATHAN B. ABBOTT and JOHN P. CRANFORD, of Brooklyn, in the county of Kings and State of New York, have invented an Improvement in Cross-Walks for Composition Pavements, of which the following is a specification:

Streets and roads have been made of composition containing bituminous material, sand, gravel, stones, and similar substances, laid down in an arched or curved surface running across the street, so as to throw the water to the gutter-ways. Pavements of this character are most easily constructed when they extend along the street or roadway with uniformity, and without any special provision for cross-walks; hence one part of the street is as clean and dry as another in fine weather, but in cases where the pavement is wet, or covered with partially-melted snow, or with water or mud, the want of a suitable crossing is manifest. We meet this want by an elevated cross-walk applied in a peculiar manner upon the composition pavement, in a strip, say, four or more feet wide across the roadway, such elevation being sufficient to cause water to run off freely and to prevent the accumulation of mud or water upon the crossing.

In the drawing, Figure 1 is a partial plan view of the end of the cross-walk, and Fig. 2 is a vertical cross-section of the same.

The roadway is laid in the usual manner with the curved or arched surface, and we then cut into the surface grooves, as seen at *a a*, for the edges of the material forming the

cross-walk, and then coat over the surface of the pavement with bituminous material in a heated condition; then spread upon the same the layer of bituminous concrete, and roll the same to form the proper convex surface for the cross-walk *b*, care being taken to prevent the surface of such cross-walk from containing any depressions in which water can lodge, and we also make the slope between the cross-walk and the surface of the roadway so gradual as to prevent undue concussion to passing vehicles.

In this mode of laying the cross-walk the roadway does not have to be prepared for said cross-walk until the roadway itself is entirely finished, which is a great advantage, especially where the heavy steam-rollers are employed to roll the pavement in various directions, because this rolling would injure the cross-walk if previously laid.

We claim as our invention—

The method herein specified of applying an elevated composition cross-walk to an asphalt pavement, by channeling the pavement for the edges of the cross-walk, and then laying said cross-walk upon the pavement, substantially as set forth.

Signed by us this 17th day of January, A. D. 1876.

NATHAN B. ABBOTT.
J. P. CRANFORD.
